UNITED STATES PATENT OFFICE.

STEPHEN J. MEEKER, OF NEWARK, NEW JERSEY.

DESIGN FOR A BRACKET-PLATE FOR LOCOMOTIVE-TENDER COUPLINGS.

SPECIFICATION forming part of Design No. 30,683, dated May 2, 1899.

Application filed April 10, 1899. Serial No. 712,538. Term of patent 14 years.

To all whom it may concern:

Be it known that I, STEPHEN J. MEEKER, a citizen of the United States, and a resident of Newark, Essex county, State of New Jersey, have invented and produced a new and original Design for Bracket-Plates for Locomotive-Tender Couplings, of which the following is a specification, reference being had to the accompanying drawings, forming part thereof,

10 In the accompanying drawings, Figure 1 is a perspective view of a bracket-plate embodying my invention, and Fig. 2 is a horizontal section through the center of the bracket-plate.

15 As shown in the drawings, the leading or material feature of my design consists of a bracket-plate having a chambered projection 1, the chamber 2 of which is narrowest at its

inner end and gradually increases in width toward its mouth or open end, the side walls 20 3 3 of the chamber being formed in straight lines throughout the greater portion of their length. The upper and lower walls of the chamber project beyond the mouth of the latter and are formed with curved faces 4 4. 25

Having thus set forth my invention, what I claim as new, and desire to secure by Letters Patent, is—

The design for a bracket-plate for locomotive-tender couplings, substantially as herein shown and described. 30

STEPHEN J. MEEKER.
